SWING

Earl H. Hurley, Emporium, Pa.

Application October 19, 1943, Serial No. 506,889

3 Claims. (Cl. 155—65)

1

This invention relates to an exercising device in the form of a swing, designed primarily as a muscle building means and excess weight reducer.

An important object of the invention is to provide a swing having an operating means embodying levers controlled by the person seated in the swing, whereby the swing will be caused to move when the operator exerts a pull on the levers, providing an exercising device with exceptional recreational and amusement qualities, due primarily, to the ease of operation.

Another object of the invention is to provide a device of this character which may be used with exceptionally beneficial results, in restoring action to injured muscles, nerves and the like, suffered by wounded members of the armed forces.

Still another important object of the invention is to provide a swing actuating means which will permit the operation of the swing with a long or short movement, with a minimum arm stroke.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is a side elevational view of a swing constructed in accordance with the invention, and illustrating the swing as supported from a wall bracket.

Figure 2 is a front elevational view thereof.

Figure 3 is a plan view of the swing and the bracket.

Figure 4 is an elevational view of a modified form of the invention, illustrating the swing as mounted on a supporting frame.

Figure 5 is a sectional view taken on line 5—5 of Figure 4.

Figure 6 is a sectional view taken on line 6—6 of Figure 5.

Figure 7 is a fragmental elevational view of a modified form of seat, illustrating a back strap as connected therewith.

Figure 8 is a fragmental detail view illustrating the hand grip of the levers, this strap being shown as connected thereto.

Referring to the drawing in detail, the supporting bracket for the swing is indicated generally by the reference character 5 and includes a rear

2

bar 6 and forwardly extended converging arms 7. The bracket also embodies a vertical bar 8 that connects with the bar 6, at a point intermediate the ends of the bar 6, as clearly shown by Figure 3 of the drawings. The reference character 9 indicates a brace bar, which extends from the upper end of the bar 8, to the forward end of the bracket proper, or at a point where the bars 7 are connected with each other.

The horizontal rod 10 is supported by the bracket, and provides the support for the swing proper, which includes side bars 11, which are provided with straps 12 at their upper ends, the straps 12 being positioned around the horizontal bar to pivot thereon.

The seat of the swing is indicated by the reference character 13 and is provided with pivot pins 14 at its ends, which operate in openings formed at the lower ends of the bars 11. The seat, while it is adapted for pivotal movement between the bars 11, acts to hold the bars 11 in proper spaced relation with respect to each other. A brace bar indicated at 15 is disposed between the bars 11, and holds the bars 11 in spaced relation at their upper ends.

The bars 7 are connected by means of the spaced bars 16 which are disposed in parallel relation with respect to each other, as clearly shown by Figure 3 of the drawings.

Journalized in the bars 16 is a pivot pin 17 to which the upper end of the operating rod 18 is pivotally connected. The lower end of the operating rod extends to a point in proximity to the operator's seat, and is connected with the member 19, through the medium of the pivot pin 20, the member 19 being formed with a cutout portion in its end, to receive the lower end of the operating rod 18. This member 19 is pivotally mounted on the rod 21 that extends between the bars 11, the ends of the rod 21 being disposed in openings formed in the bars.

Spacers 22 are disposed on the rod 21, between the member 19 and inner surfaces of the bars 11, to the end that the member 19 will be held properly centered on the rod 21 and at the same time, will be permitted to pivot freely on the rod 21.

Handles indicated at 23 are connected with the member 19, and extend downwardly to positions where they may be readily grasped by the person seated on the seat 13, to operate the swing.

As clearly shown by Figure 1 of the drawings, the operating rod extends at an oblique angle with respect to the bars 11, under normal conditions, and the member 19 extends at an oblique

angle with respect to the operating rod 18, so that a pull on the handles 23, will tend to push the lower ends of the bars 11 forwardly.

In the form of the invention as illustrated by sheet 2 of the drawings, the swing is shown as supported by the supporting frame which includes end members 25, each of which end members includes inclined bars 26 that cross each other near the upper ends thereof, the lower ends of the bars 26 being connected to the horizontal base bars 27, at points in spaced relation with the ends of the base bars 27. The end members are held in spaced relation with respect to each other, by means of the transverse bars 29, which connect with the bars 26 at their upper ends. The frame also includes inclined brace bars 30, that connect with the central transverse bar 31, and have their upper ends connected with the bars 26. End bars 32 have connection with the transverse bars 29, and are provided with openings in which the ends of the supporting rod 33 are positioned, the supporting rod 33 providing a support for the cables 34, which are shown as looped around the rod 33 and secured thereon, in such a way that the cables may pivot on the rod when the swing is in motion.

The lower ends of the cables 34, extend through openings in the seat 35, where they are secured.

While the operating mechanism in this form of the invention, is similar to the operating mechanism as illustrated on sheet 1 of the drawings, the cables are braced, by means of the bars 36. Eye-bolts 37 extend through the bars 36, at the ends thereof, the cables being extended through the eye-bolts which eye-bolts are secured firmly in position, by means of the nuts 38. The eye-bolts 37 are partially embedded in the bars 36, to prevent rotation of the eye-bolts.

Connected to the bars 29, are spaced parallel bars 39 which are formed with openings in which the ends of the pivot pin 41 are mounted, the operating bar 42, being shown as pivotally mounted on the pivot pin 41. The lower end of the bar 42 has pivotal connection with the member 43, which in turn is pivotally mounted on the rod 44 that extends through bearing openings in the bars 36. Handles 45 are connected with the member 43 and are so disposed that they may be readily gripped by an operator seated on the seat. Wrist straps 46 are secured to the han-

dles 45 and are provided with loops 47, which encircle the wrist of the operator so that in the event that the operator's grip slips, the hands of the operator will be held adjacent to the handles so that the handles may be again readily gripped for operation.

As shown by Figure 7, the swing seat which is indicated by the reference character 48, is supported between the pivot bars 49, the bars 49 being formed with elongated openings, through which the back strap 50 extends, providing a back rest for the operator to insure against the operator falling rearwardly, from the swing.

What is claimed is:

15 1. In a swing, a support, a supporting rod on the support, a pair of seat supporting cables pivotally mounted on the supporting rod, rigid bars secured to the cables, in parallel relation therewith, an actuating rod pivotally connected with 20 said support, an operating member pivotally mounted between the rigid bars, and to which the actuating rod is pivotally connected, and handles connected with the operating member to be 25 pulled by a person sitting on the seat of the swing.

2. In a swing, a support, a supporting rod on the support, a pair of seat supporting cables pivotally mounted on the supporting rod, an actuating rod pivotally connected with said support, 30 means for connecting the actuating rod to said cables comprising an operating member pivotally mounted between the cables and to which said actuating rod is pivotally connected, handles connected with the operating member, and by 35 means of which the actuating rod is operated, and wrist straps secured to the handles and adapted to connect the wrists of a person seated on the seat of the swing, with the handles.

3. In a swing, a support, a supporting rod on 40 the support, a pair of seat supporting cables pivotally mounted on the supporting rod, rigid bars secured to the cables, in parallel relation therewith, an operating bar pivotally connected with said support, an operating member connected to the rigid bars and being also connected to the operating bar, and handles connected with the operating member to be pulled by a person sitting on the seat of the swing, operating the swing.
